US0D1072733S

(12) **United States Design Patent** (10) **Patent No.:** **US D1,072,733 S**
(45) **Date of Patent:** **** Apr. 29, 2025**

(54) **WIRELESS CHARGER**

(71) Applicant: **Shenzhen Tengsai Technology Co., LTD**, Shenzhen (CN)

(72) Inventor: **Guangming Hu**, Shaoguan (CN)

(73) Assignee: **Shenzhen Tengsai Technology Co., LTD**, Shenzhen (CN)

(**) Term: **15 Years**

(21) Appl. No.: **29/914,521**

(22) Filed: **Oct. 18, 2023**

(51) LOC (15) Cl. **13-02**

(52) U.S. Cl.

USPC **D13/108**

(57) **CLAIM**

The ornamental design for a wireless charger, as shown and described.

DESCRIPTION

FIG. 1 is a rear perspective view of a wireless charger, showing my new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view, shown in a state of use; and, FIG. 10 is a perspective view of its open state.

The broken lines in the drawings illustrate the portions of the wireless charger, which form no part of the claimed design.

1 Claim, 10 Drawing Sheets
